(57) **CLAIM**

The ornamental design for a wheel, as shown and described.

DESCRIPTION

FIG. 1 is a front elevational view of the wheel in accordance with my new design; and,

FIG. 2 is a perspective view thereof.

The broken line showings of the central circle, the small circles around the hub area and the valve stem aperture are for illustrative purposes only and form no part of the claimed design.

1 Claim, 1 Drawing Sheet

FIG. 1

FIG. 2
